UNITED STATES PATENT OFFICE.

HOWARD EARL HOOVER, OF CHICAGO, ILLINOIS, ASSIGNOR, BY MESNE ASSIGNMENTS,
TO THE HOOVER COMPANY, OF NORTH CANTON, OHIO, A CORPORATION OF OHIO.

SUCTION CLEANER.

Application filed August 8, 1917. Serial No. 185,200.

To all whom it may concern:

Be it known that I, HOWARD EARL HOOVER, a citizen of the United States, residing at Chicago, in the county of Cook and State of Illinois, have invented a certain new and useful Improvement in Suction Cleaners, of which the following is a specification.

My invention is illustrated more or less diagrammatically in the accompanying drawings wherein—

Figure 1 is a plan view with parts broken away;

Figure 2 is a section along the line 2—2 of Figure 1;

Figure 3 is a side elevation;

Figure 4 is a section along the line 4—4 of Figure 2;

Figure 5 is a section along the line 5—5 of Figure 1;

Figure 6 is a section along the line 6—6 of Figure 1;

Figure 7 is a front elevation.

Like parts are indicated by like characters in all the figures.

A is a suction cleaner housing. It contains a fan chamber A¹, a suction or brush chamber A² communicating with the fan chamber through the port A³, and it has an open suction mouth A⁴. A⁵ is a motor housing mounted on the rear side of the suction cleaner housing A. It contains a motor armature A⁶ mounted on a shaft A⁷. A⁸ is a suction fan carried by the shaft A⁷ mounted for rotation in the fan chamber A¹. A⁹ A¹⁰ are front fixed supporting wheels mounted for rotation on the axles A¹⁰ on brackets A¹¹ projecting rearwardly from the rear wall A¹² of the suction chamber A² so that the supporting wheels are immediately behind the open suction mouth and located between the planes passing through the ends of the suction mouth or nozzle.

These wheels are so located in order that the sweeper may be run out to the edge of the rug without danger of their running off and allowing the weight of the mechanism to rest upon the nozzle.

B B are lugs depending downwardly from the motor housing A⁵ and spaced apart. B¹ is a shaft extending between them. B² B² are supporting levers rotatably mounted on the shaft B¹ joined adjacent such shaft by the sleeve B³. B⁴ is a shaft passing through the outer ends of such levers upon which

are mounted the separated wheels B⁵ B⁵. B⁶ is a nut located between the opposed ends of said levers held in position between such ends by set screws B⁷ upon which it is pivotally mounted. B⁸ is an adjusting screw screw-threaded in the nut B⁶ slotted as at B⁹ so that it may be rotated by means of a screwdriver. It has a round head B¹⁰ engaging a pocket B¹¹ on the under side of the motor housing A⁵ whereby the levers may be rocked about the shaft B¹ by rotation of the screw. The wheels B⁵ are so spaced apart that their outer sides are located substantially in a vertical plane tangential to the opposed sides of the cylindrical motor housing.

The motor A⁶ does not occupy the entire length of the motor housing A⁵. C is a wall closing off that part of the housing containing the motor. C¹ is a sleeve concentric with the motor housing integral at one end with the wall C and at the other end with the wall C² which forms the rear wall of the fan chamber A¹. This sleeve contains the bearings C³ C⁴ which support the shaft A⁷. Between these bearings is a worm C⁵ rigidly mounted on the shaft. This worm is in mesh with a worm gear C⁶ on the cross shaft or jack shaft or power transmitting shaft C⁷. C⁸ is a housing depending downwardly from the sleeve C¹ and completing a closure which contains the worm and worm gear and a portion of the shafts A⁷ and C⁷ and which carries bearings C⁹ C⁹ in which the shaft C⁷ is rotatably mounted. The shaft C⁷ extends out parallel with the suction mouth toward one end of the suction cleaner casing being enclosed within a sleeve C¹¹ communicating with the housing C⁸. This sleeve contains at its outer end a bearing C¹² in which the shaft is mounted and is itself rigidly attached to a belt housing C¹² extending rearwardly and upwardly from one end of the suction chamber A². The shaft C⁷ projects through such bearing in such chamber and carries at its end within the chamber the belt pulley C¹⁴.

Mounted for rotation within the suction chamber A² adjacent the open mouth A⁴ is a sweeping and heating brush D made up of a hollow brush body D¹ from which project the spaced and separated bristle groups D². This brush body contains at either end bearing sleeves D³ rotatably mounted upon a

fixed shaft D⁴. This fixed shaft is removably mounted in supporting plates D⁵ pivoted on the inner sides of the end walls of the suction housing whereby the brush may be moved in or withdrawn from the open mouthed suction housing. Mounted on these plates D⁵ surrounding the shaft D⁴ are perforated flanged guard plates D⁶. These plates are located between the ends of the brush and the plates D⁵ and the flange D⁷ thereon overhangs the end of the brush but is out of contact therewith. D⁸ are perforations through the ends of the suction chamber, and D⁹ are perforations through the plates D⁵. These perforations are in register and communicates with the open space between the guard plates and the plates D⁵ so that air may be drawn through such perforations into such open spaces, pass thence through the perforations in the guard plates and out between the flanges D⁷ and the ends of the brush. D¹⁰ is a removable belt pulley on one end of the brush. The pulley is so placed in order that the bristles may be evenly arranged along the entire length of the brush without interruption so that there will be no unswept portion of the carpet and thus the effective length of the brush is not decreased. It partially overhangs the flange D⁷ but is out of contact with it. C¹⁰ is a belt travelling over the pulleys D¹⁰ C¹⁴ whereby the brush may be rotated by the rotation of the shaft C⁷. D¹¹ is an aperture in the outer side wall of the housing C¹³ closed by a removable plate D¹² whereby access may be had to the belt pulley C¹⁴ and end of the shaft C⁷ for adjustment of the parts or for a removal of the belt from the pulley when for some reason it is desired to cease the power driving of the brush. C¹⁵ is a hole in the housing C¹³.

F is an aperture in the downwardly and forwardly inclined upper wall of the suction housing A². It is normally closed by means of the removable plate F¹. It is bounded by an inwardly extending flange F² which flange on its upper side extends clear in to join the wall F³ surrounding the upper portion of the port A³. F⁴ is a sleeve adapted to penetrate the port F. It is slotted at F⁵ to engage a pin F⁶ on the flange F² whereby the sleeve will be compelled always to penetrate the opening F in the same direction. This is necessary because the sleeve is cut off along a diagonal plane owing to the fact that it must close completely the port A³. If the sleeve before being inserted were to be rotated there would be the possibility that the longer portion F⁷ might pass in through the port A³ and be engaged by the fan. F⁸ is a reduced portion adapted to be engaged by the suction hose F¹⁰.

G is a discharge passage extending outwardly from the fan chamber A¹ in a gen-

erally tangential direction. It has a curved wall G¹ and terminates in a rearwardly open port G². G³ is a flange surrounding such port G². G⁴ is a sleeve provided with diametrically opposed lugs G⁵ G⁶ adapted to engage screw holding bolts G⁷ G⁸. The lug G⁵ is provided with a radial slot to engage the bolt G⁷, the lug G⁶ with a tangential slot being adapted to engage the bolt G⁸. Thumb nuts G⁹ on said bolts are adapted to clamp the sleeve G⁴ rigidly against the flange G³. G¹⁰ is a large open mouthed bag its open mouth surrounding the sleeve G⁴ and held in position thereon by the contractile collar G¹¹. This bag is impervious to dust but permits the air to pass through, and forms therefor the usual dust receptacle into which the dust laden air is discharged by the suction fan.

The upper portion of the motor housing A⁵ is apertured as at H immediately behind the fan chamber A¹. Located within this aperture is an electric switch H¹ contained partially within the housing and projecting partially thereabove. H² is the switch lever which may be operated by the foot or hand of the operator. H³ is a sleeve in the wall of the motor housing A⁵ communicating with that portion of the housing occupied by the switch H¹. H⁴ is an electric conductor passing inwardly through such sleeve and communicating with the switch. H⁵ is an electrical conductor communicating with the switch and passing through the aperture H⁶ in the wall C to communicate with and provide power for the operation of the motor A⁶. The conductor H⁴ communicates with any suitable source of power not here indicated for furnishing the electric current to the motor to operate the apparatus.

J is a handle bail pivoted on pins J¹ J¹ on opposed sides of the motor housing A⁵. This handle bail is curved upwardly as indicated at J² in order that the greatest height of the machine will be in line with the fan chamber and the cleaner can thus be run far under low pieces of furniture before the handle beyond the bail contacts with the lower part of the furniture, and thus without the necessity of lowering the handle to a position parallel with the floor. It is large enough to clear the rear end of the motor housing A⁵. J³ is a handle mounted in the socket J⁴ on the handle bail.

A good many features of the suction sweeper to which I have referred are not here shown in detail and where some are shown more or less in detail they are not described. This is because they form no part of the subject matter of the present invention and as to some of them because they have been elsewhere in other applications made the subject of claims. I wish it understood that while the drawings here present

ed are in fact based upon a working machine the same are for the purposes of this case to be taken as diagrams and not as necessarily limiting me to the particular 5 structure shown. It will be obvious that very considerable variations in size, shape and proportions of some or all of the parts together with the substitution of others for some of those here shown could be made 10 without departing from the spirit of my invention.

The use and operation of my invention are as follows:—

The motor is enclosed so no dust can reach 15 the bearings from that side. The fan tends to throw the dust away from the bearings so that there is little tendency for dust to work in except as it may settle on the end. Thus all the bearings except the brush bearings 20 themselves are outside the line of travel of any dust particles borne by the dust laden air. All the mechanisms interposed between the motor shaft and the brush which cooperate to drive the brush are located outside 25 the path of the dust laden air.

The dust laden air which is projected out tangentially from the fan is guided by the curved wall of the discharge passage into a discharge opening parallel with the axis of 30 the fan where it is discharged into a dust bag. The dust bag is of the ordinary type and is fastened in position on a flange surrounding the opening by means of two lugs one of them with a radial slot engaging a 35 fixed pin. The parts are brought together by first engaging the pin with this slot and then swinging the bag sleeve over so that a tangential hook on the opposed side engages another pin and the parts may then be 40 locked into position. In this arrangement there is no possibility of the bag being accidentally disengaged because it is necessary first to rotate the whole bag and sleeve before the tangential hook can be disengaged 45 and then to lift up the whole bag and sleeve before the radial slot can be disengaged.

The passageway from the brush chamber to the fan chamber is reduced to a minimum length or occupies but a minute portion of 50 the brush chamber which includes both the fan chamber and this passageway. This brings the brush chamber proper and the fan chamber into close relation and the particles picked up by the brush and projected 55 rearwardly and upwardly along straight lines may actually without any change of direction merely by the force given them by the brush be thrown into the fan chamber where they may be driven off by the fan. 60 In other words this apparatus is so arranged that it will be possible to pick up a heavy particle so heavy that the air could not move it at all and carry it through the apparatus and discharge it in the dust bag merely by 65 the projecting power of the brush and then

of the fan without any reference whatever to the carrying power of the air.

The hole C¹³ in the housing C¹³ will permit a small amount of fresh air from the outside to pass through said housing and be 70 taken out with the current of air passing through the machine. The object of such an arrangement if it becomes necessary though it might not be in many cases necessary, would be to clear the otherwise dead air 75 space in this housing and thus tend further to protect the bearings and the operative parts from dust and dirt.

The worm housing C⁸ is adapted to hold a lubricant which is fed up into the operating 80 parts. The casting is so arranged that its split portion, that is the split between the upper and lower portion, is placed high up and far above the drive gear and far above the level of oil which under any ordinary 85 conditions would be maintained in this housing. This tends to reduce the danger of leakage or escape of oil at such split.

The casing is so arranged that it presents 90 one and the same surface to which the bag is attached and also to which the motor casing is attached. This surface in the case shown is substantially vertical, though it might be inclined, but by thus having these two parts, the bag connections and the motor 95 casing, attached to surfaces in the same plane the processes of manufacture are greatly facilitated.

I claim:

1. In a suction cleaner, a casing, a frame 100 pivoted intermediate its ends on a long fulcrumed pin to the bottom of the casing, widely separated rollers rotatably mounted on one end of the frame and beneath the casing, a screw device swiveled to the bottom 105 of the casing and screw threaded to the other end of the frame.

2. In a suction cleaner, a casing, a frame pivoted intermediate its ends on a long fulcrumed pin to the bottom of the casing, 110 widely separated rollers rotatably mounted on one end of the frame and beneath the casing, a screw device swiveled to the bottom of the casing and screw threaded to the other end of the frame, said screw device containing 115 a head whereby it is suspended on the bottom of the casing and a screw slot in its other end whereby it may be rotated.

3. A suction cleaner comprising a case with an inlet opening and a suction chamber, a motor mounted on the case, a brush mounted near the inlet opening, a power transmission device connecting the motor and the brush and containing a pulley on the brush, a belt operatively connecting the motor with said pulley, a belt housing at one end of the case and substantially closed except at the end where it opens into the suction chamber and its forward part forming 125 part of the suction chamber and a jack shaft 130

- connected at one end with the motor and at the other projecting through the wall of the belt housing and provided with a pulley to receive the belt.
5. 4. A suction cleaner comprising a case with an inlet opening and a suction chamber, a motor mounted on the case, a brush mounted near the inlet opening, a power transmission device connecting the motor and the brush and containing a pulley on the brush and a belt operatively connecting the motor with said pulley, and a belt housing at one end of the case and substantially opening into the suction chamber and its forward part forming part of the suction chamber at one end and provided at the other end with an opening and a closure therefor.
5. A suction cleaner comprising a case with an inlet opening and a suction chamber, a motor mounted on the case, a brush mounted near the inlet opening, a power transmission device connecting the motor and the brush and containing a pulley on the end of the brush, a belt operatively connecting the motor with said pulley, a belt housing at one end of the case and substantially closed except at the end where it opens into the suction chamber and its forward part forming part of the suction chamber, and at the other end a shaft projecting through the wall of the belt housing and provided with a pulley to receive the belt, said belt housing provided with an opening beyond the pulley and a closure therefor.
6. In a suction cleaner the combination of a casing having an inlet opening and a suction chamber with a brush near the inlet opening, a motor mounted on the casing and power transmission means from the brush to the motor comprising a belt, a pocket which encloses the same and forms part of the suction chamber, and a jack shaft from the motor to the belt.
- 45 7. In a suction cleaner the combination of a casing having an inlet opening and a suction chamber with a brush near the inlet opening, a motor mounted on the casing and power transmission means from the brush to the motor comprising a belt, a pocket which encloses the same and forms part of the suction chamber, a jack shaft from the motor to the belt and a sleeve which surrounds the jack shaft.
- 55 8. In a suction cleaner the combination of a casing having an inlet opening and a suction chamber with a rotating part in the suction chamber near the inlet, a motor mounted on the casing and power transmission means from the rotating part to the motor and housing or pocket, which encloses such power transmitting means and at one end opens into and forms part of the suction chamber and is provided with a free air inlet opening at its other end.
9. In a suction cleaner the combination of a casing having a suction chamber and an inlet with a brush mounted near the inlet, a fan housing forming a fan chamber, a fan therein, said chamber connected to said suction chamber and provided with an outlet, and a brush driving mechanism comprising a motor and a transmission mechanism therefrom to the brush lying wholly outside of the path of the dust laden air, a housing for the motor separate from said fan housing, and a housing for a portion of the transmission mechanism between them, an additional housing partially closed along its bottom which contains the transmission mechanism connected with the brush and which opens into and forms part of the suction chamber.
10. In a suction cleaner the combination of a casing having a suction chamber and an inlet with a brush mounted near the inlet, a fan motor housing and a fan chamber between said housing and the suction chamber, a fan within said fan chamber, said fan chamber connected to the suction chamber and provided with an outlet, a fan and brush driving mechanism comprising a motor and transmission mechanism therefrom to the brush lying wholly outside of the path of travel of the dust laden air, a belt forming part of the transmission mechanism, said motor housing separate from said fan housing and a housing partially closed along its bottom which contains the belt and which opens into and forms part of the suction chamber.
11. In a suction cleaner the combination of a casing having at one end a brush and fan and housing therefor and at the other a motor and housing therefor, said housings separated, transmission mechanism located intermediate the said housings, and including a belt from the motor to the brush and a housing therefor, said belt lying outside the path of travel of the dust laden air, a housing partially closed along its bottom containing the transmission mechanism, connected with the brush, which housing opens into and forms part of the suction chamber.
12. In a suction cleaner the combination of a casing having an inlet with a brush mounted near the inlet, a fan, a motor, a shaft for the motor and shaft bearings for the same, transmission mechanism from the shaft including a connection which leads to the brush, said transmission mechanism, motor and all the bearings except those of the brush lying outside of the path of travel of the dust laden air, a housing partially closed along its bottom which contains the transmission mechanism connected with the brush and which opens into and forms part of the suction chamber.
13. In a suction cleaner a rear support

comprising a frame mounted upon the bottom of the casing by a long pivot pin, wide spread rollers mounted on one end of the frame, a screw rotatably supported from the 5 bottom of the casing, a nut in which it is screw-threaded and lateral screws on the frame impinging the nut.

14. In a suction cleaner the combination of a casing having a suction chamber and 10 within the suction chamber a suction mouth, and a brush mounted adjacent said mouth driving means for said brush and a housing for such driving means placed out of line with the bristles of the brush whereby the 15 rotating bristles do not throw particles into the driving means housing, the housing opening only into the suction chamber and forming part of the suction chamber.

15. In a suction cleaner the combination 20 of a casing having an inlet with a brush mounted adjacent said inlet, a driving

means for rotating the brush, a casing for such driving means said casing opening into so as to form part of the brush chamber at one end and provided with an opening at 25 the other and means for drawing a current of air through such last mentioned casing and the inlet mouth.

16. A suction sweeper casing including a suction nozzle, a rotating brush therein, a 30 belt housing leading therefrom, a pulley on said brush, said belt housing being attached to the casing and closed except where it opens into the suction chamber to permit passage of the brush operating means. 35

In testimony whereof I affix my signature in the presence of two witnesses this 27th day of July, 1917.

HOWARD EARL HOOVER.
